CLAIM

I claim the ornamental design for a socket, as shown and described.

DESCRIPTION

FIG. 1 is a top perspective view of a socket in accordance with the present design;

FIG. 2 is a bottom perspective view of the socket of FIG. 1;

FIG. 3 is a top plan view of the socket of FIG. 1;

FIG. 4 is a bottom plan view of the socket of FIG. 1;

FIG. 5 is a back side elevational view of the socket of FIG. 1;

FIG. 6 is a front side elevational view of the socket of FIG. 1;

FIG. 7 is a right side elevational view of the socket of FIG. 1; and,

FIG. 8 is a left side elevational view of the socket of FIG. 1.

The broken lines shown in the drawings are for the purposes of illustrating portions of the article and form no part of the claimed design.

The broken away symbols in the drawings indicate the appearance of any portion of the article between the break lines forms no part of the claimed design.
